UNITED STATES PATENT OFFICE

160,834

ELEVATOR STARTER'S PANEL

Morrison John Brounn, Flushing, N. Y., assignor
to Otis Elevator Company, New York, N. Y., a
corporation of New Jersey

Application October 14, 1949, Serial No. 5,495

Term of patent 14 years

(Cl. D26—5)

To all whom it may concern:

Be it known that I, Morrison John Brounn, a citizen of the United States and a resident of Flushing, county of Queens, State of New York, have invented a new, original, and ornamental Design for Elevator Starter's Panel, of which the following is a specification, reference being had to the accompanying drawing, forming part thereof.

In the drawing:

The figure is a view in perspective of an elevator starter's panel showing my new design.

What is claimed is:

The ornamental design for an elevator starter's panel, substantially as shown.

MORRISON JOHN BROUNN.
